SUCTION-ROLL SHELL DRILLING

Application filed November 23, 1928. Serial No. 321,406.

The present invention relates to paper making machinery and more particularly to the disposition or distribution of the drilling or perforations of the shell for the suction roll.

The suction rolls in general use in machines of this type are perforated throughout their operative surface with a great number of small diameter closely placed and radially disposed holes. Wherever the metal of the shell is thus cut or drilled through it is weakened to just that extent. In the larger machines these large cylindrical shells, when used for couch rolls, measure as much as 15 30" to 36" diameter by 25' length. Such shell is supported only at its extreme ends. When used as a press roll of corresponding proportions it is also supported at its extreme ends but must, in addition, sustain 20 the weight of the cooperating top press roll. In practice, the drilling of these large shells is made by a multiple spindle machine, a great number of drills all acting at one time to produce a corresponding number of perforations. To provide a uniform spacing between the drill holes and a uniform distribution throughout the surface of the shell, an indexing plate is provided.

As is well known, these shells comprise the 30 revolving or movable member of the suction roll assembly, the stationary member being the suction box supported in well known manner therewithin. The box, as is well known, in assembling, is so adjusted relatively to the 35 enclosing shell as to maintain a light running contact between the box packing and inner shell surface or wall. In the modern paper making machine, the shell surface travels at a high speed, often as 40 high as 1000 ft. per minute or more. In the paper stock there is more or less foreign matter of a gritty or abrasive nature which passes through the perforations of the shell. A certain portion of this, 45 invariably follows the inner wall of the shell and is picked up or engaged by the box packing. The packing, itself, in its light rubbing contact with the shell wall has a slight abrading action, even under the most 50 favorable circumstances. The continual ad-

dition of the foreign matter multiplies this grinding action. This scores the inner wall of the shell into alternate circumferential ridges and grooves so that many shells, after a few years use must be rebored. Obviously, 55 this reboring can not be carried beyond certain safety limits. The shell wall thickness can not be reduced beyond that essential to withstand the strains imposed by the working conditions to be met in operating the 60 machine.

The main purposes of the present invention are to overcome these and other serious objections, and, at the same time, provide 65 a drilling or perforation which may be easily and quickly applied to a suction roll shell.

In order to more clearly disclose the construction, operation, and use of the invention reference should be had to the accompanying 70 drawings forming part of the present application. Throughout the several figures of the drawings like reference characters designate the same parts in the various views.

In the drawings:—

Fig. 1 is a fragmentary side elevation of a 75 suction couch roll with the invention applied;

Fig. 2 is a top plan view of the same roll, showing the invention in diagram, the invisible perforations being shown in dotted line, and only two rows;

Fig. 3 is a vertical cross section in a plane at right angles to the longitudinal axis of the roll on line 3—3 of Fig. 1; and

Fig. 4 is a plan view of the fragment of Fig. 1 split longitudinally on line 4—4 of Fig. 2, and flattened to develop the lines of the drilling.

It will be obvious to those skilled in the art that drawings of a roll of the size used, when reduced to such size as is required for a patent application, can not be kept in exact proportion as to such matters as the perforations or the relative positions of the lines of perforations, etc. These features are, necessarily, considerably enlarged or exaggerated in order to more clearly and definitely bring out the ideas of the invention. For instance, the diameter of drill hole in a couch shell is about $\frac{5}{16}$ of an inch end, in one known type of drilling, the distance between centers 100

of perforations in the same row, circumferentially of the roll is 1.0162 inches and, longitudinally, .5666 inches. For a shell 30 inches in diameter by 25 feet long, a proportionate reduction would nearly eliminate the 5 perforations and run the lines so close as to confuse. The shell illustrated is for a suction press roll. For couch roll drilling the perforations are of greater diameter than for 10 press roll drilling and have their outer ends counter sunk. Likewise, there is a difference between the drilling for first and second press rolls, all as will be well understood.

After a shell has been drilled the inner 15 wall which, in operation, travels at high speed across the contacting surface of the packing strips of the suction box presents many thousands of small diameter round holes each surrounded by a metal edge. As 20 these edges cross the packing strips they act to plane them down. Consequently, where planed in this manner, the packing and grit or other foreign matter, has little or no opportunity to wear the inner surface of the 25 shell. On the other hand, where it is not so planed, the shell is worn away, leaving grooves with intervening ridges. In other words, this planing action keeps the planed 30 portion of the packing from wearing the shell surface. Heretofore, the perforations have been so distributed that they do not plane, equally, all parts of the packing strips. The result in principle, is the same as though 35 the packing strips were not planed at all—the shell is badly scored.

For simplicity and clearness of illustration, the shell only has been shown, with its perforations, apart and removed from the assembled organizations in which it, necessarily, 40 must always be used. Its relative position in and cooperation with the particular parts of the machine when used, variously, as a couch, press, transfer, or other suction roll need no further elaboration here and will all be readily understood by those skilled in the 45 art. Likewise it is my understanding that all such assemblies and combinations fall within the scope of this invention when they comprise a shell having the type of drilling or perforation herein disclosed.

By the present construction, arrangement and disposition of the perforations, the planing action is uniform throughout the entire surface of the packing strips so that there 55 are no sections capable of exciting a greater grinding or abrading action than any other section. Consequently, the inner shell surface is evenly worn and does not need reborning at any time.

60 Referring to the drawings in detail, 1 indicates the shell. It is perforated throughout its operative surface with the particular type of perforation best adapted to the purpose of its use—such as couch, press, transfer, etc.

65 According to the present invention these per-

forations are disposed on a plurality of endless parallel curved lines each making a single complete circumferential traverse of the shell and the several lines being closely spaced apart longitudinally of the shell. Preferably 70 these lines alternate, the perforations of the intermediate ones being spaced slightly circumferentially relatively to those of the lines immediately adjoining on either side.

Each circumferential line comprises a compound of two opposite curves of the same total length and inclination or pitch. In the particular example selected for the purpose of illustrating the present invention, these curves of each such compound are half-helices or helicoidal for one-half of a single circumference. Since the two half-helices are oppositely directed or inclined and are of the same pitch or angularity their ends will exactly align, making one continuous curve, one half being directed and inclined oppositely and equally to the other. Each such circumferential line is complete in itself and spaced from those adjacent. No two or more merge or connect one with another. Or, briefly, the two halves of each such endless row may each be considered as one half of a single complete circumferential turn or rotation which forms a single helix of a finely pitched screw thread which, if uninterrupted, 90 would run from end to end of the shell, each such half being in continuation of the other and being inclined and directed oppositely thereto, so that the two ends of the two halves align to produce a single continuous circumferential doubly and reversely curved row. It will also be obvious that in reversing one half of each helix relatively to the other, the screw thread is broken or interrupted at each helix and converted into a corresponding 95 number of separate, parallel, spaced, endless, doubly and reversely curved, continuous, circumferential rows each running once completely around the shell. While the curve above described has been set forth as consisting of two parts of equal length it is to be understood that other fractions of the total helix may be used, provided such fractions combine to produce a single, continuous circumferential row extending once completely 100 about the shell and having one or more portions inclined and directed oppositely to one or more other portions thereof. For instance, the successive helices may be each divided into four, six, eight, twelve and so on equal parts, the alternate parts being oppositely disposed. The resulting circumferential rows would have a wave-like, sinuous, or convolute outline, but each complete such 105 row would be parallel with and to all the others.

It will be obvious that in passing across any one given point of the packing strip of the suction box which forms a part of all such rolls, the perforations of one half of any such 110

circumferential line will act oppositely thereon to the action of the other half of the perforations in such line. Thus, whereas, the perforations in the first half being distributed helicoidally from the direction of one end toward the direction of the other end will have a tendency to feed the packing in the direction of their incline, the perforations of the other half, being distributed oppositely, will 10 act equally in the opposite direction. Thus, each half of each revolution of the shell will have its longitudinal feeding tendency exactly offset or counteracted by that of the other half and there will be no resultant longitudinal feeding action in either direction. 15 Of course, this applies equally to all cases where the circumferential rows are made up of an equal number of equally oppositely inclined and directed curvatures whether such 20 parts constitute halves, quarters, eighths or other parts of one entire row.

In the present instance, though merely for illustrative purposes, the form arbitrarily selected is that of the two-part circumferential 25 row, or, in other words, a single endless circumferential row consisting of two parts of equal length, each part being equally but oppositely inclined or directed relatively to the other such half, the two thereby aligning or 30 merging to form one smooth continuous uninterrupted circumferential row.

In order to somewhat more thoroughly distribute the perforations throughout the entire operative shell wall and thereby completely 35 eliminate any unplanned packing strip surface, a second series of rows may be disposed intermediate of and alternating with those of the first. Such second series will be slightly spaced circumferentially relatively to the 40 first series so that the holes of each corresponding circumferentially one to the other will not fall in the same lengthwise lines parallel to the longitudinal axis of the roll. Such second series has been illustrated in the present 45 case. It is to be understood that the circumferential spacing is not limited to alternate rows. The successive rows may be so spaced, throughout a considerable number. Thus, in a group of four rows or any other practical 50 and desired number, each may be slightly circumferentially spaced relatively to the last preceding and the row following the last of such group may be given the same relative circumferential position as that of the first row 55 of such group. The grouping shown in the drawings is the simplest and most readily illustrated and described within the field of the invention.

In the case illustrated a cross section at 60 right angles to the longitudinal axis of the shell and therefore, when assembled, to the packing strips of the suction box, has been arbitrarily taken and is shown in Fig. 3.

This is the path of the perforations crossing 65 that point of the packing. There would be as

many such sections, in the length of the shell, as there are circumferential rows in any one series of perforations, two alternating series being shown in this case. The section shown in Fig. 3 passes through a point midway between the ends of each half-helix composing one row of a first series or row 2. It passes diametrically through the centre of a perforation. It will be seen that at the opposite diameter of the shell it passes the same way 70 through a corresponding perforation of the other and opposite half-helix. Reading Fig. 3 in a clock-wise direction, the section from the point where it passes diametrically through the perforation of row 2 cuts only 75 slightly through the right hand side of the next perforation of that row, misses entirely the next, then cuts very slightly the third from the last perforation of the next row to the right of row 2 which I will refer to as row 3. 80 The two half helices of row 3 are designated 3^a and 3^b, the half 3^a being the last half or, as read on Fig. 3, the first half intersected by the section line. Continuing, the section line will cut, successively, more deeply through 85 the perforations of the part 3^a until it reaches a point about one-quarter around the shell, where it will pass about diametrically through a perforation. From this point the cut will decrease in the same manner in which 90 it previously increased until it reaches a point where it again passes into the perforations of row 2 at a point diametrically opposite, in the shell, to where it started in row 2. Following the section in the same direction, in 95 the lower half of Fig. 3, beginning with the diametrical cut of the perforation in row 2, the next will be cut much less deeply, the following one will be skipped, and the cut will then intersect the third from the middle perforation of the next row on the left, or row 1, 100 the two halves of which are indicated as 1^b and 1^a, reading Fig. 3 in a clockwise direction. It will be noticed that the cut through the 105 perforations of row 1 is, in cross section, the same as that through row 3. However, it is the reverse half of the helix with the curve inclined reversely. The cut through the perforations deepens from the right side of the row, relatively to row 2, to the full diameter 110 cut at the bottom of Fig. 3 and then decreases until it passes out of row 3, skips a perforation in row 2 and then cuts slightly the left of the row 2 perforation preceding the first one with a full diameter cut. 115

The path of the cut and therefore the successive perforations crossing any point on the packing strip is clearly shown on Fig. 4.

Rows 1 and 3 are second series rows or 120 rows of a series somewhat circumferentially offset relatively to row 2.

It will be noticed that, the first perforation to act on the packing is that of row 2, the next is also row 2 but only a small part of that one acts on the same spot or, the next 130

- one acts only on a part of that spot. The next is in the α half of row 3. This point to the quarter circle or 90° point there is a steady increase until full diameter is again reached, 5 which means that the area acted upon steadily increases and in the same direction until the original area acted upon is reached. It then decreases back to the starting point, as to size, of row 3^a, and then the full size again of row 10 2. Thus whatever tendency there may be, by rotation of the shell across the packing, to feed either shell or packing longitudinally relatively to the other, is offset or counter-acted, the tendency in one quarter circumference being just matched in the reverse by 15 that of the next succeeding quarter circumference. Thus all tendency toward relative longitudinal movement as between shell and packing is completely eliminated and, at the same time every part of the packing surface 20 is equally and thoroughly acted upon and planed by the perforation edges.
- Having thus described my invention, what I claim and desire to protect by Letters Patent is:—
- 25 1. A suction roll shell for paper making machines provided with a plurality of endless lines of perforations each comprising several curves. 85
- 30 2. A suction roll shell for paper making machines provided with a plurality of endless lines of perforations each comprising several merged curves. 95
- 35 3. A suction roll shell for paper making machines provided with a plurality of endless lines of perforations each comprising oppositely directed curves. 100
- 40 4. A suction roll shell for paper making machines provided with a plurality of endless lines of perforations each comprising equally and oppositely directed curves. 105
- 45 5. A suction roll shell for paper making machines provided with a plurality of parallel closely spaced endless lines of perforations each comprising oppositely directed curves. 110
- 50 6. A suction roll shell for paper making machines provided with a plurality of circumferential parallel closely spaced endless lines of perforations each comprising oppositely directed curves. 115
- 55 7. A suction roll shell for paper making machines provided with a plurality of endless lines of perforations disposed in several series, said lines being arranged parallel and closely spaced and each such line comprising several curves. 120
- 60 8. A suction roll shell for paper making machines provided with a plurality of endless lines of perforations, each such line comprising oppositely and equally inclined part-helices. 125
- 65 9. A suction roll shell for paper making machines provided with a plurality of endless lines of perforations each such line comprising several curves and said lines being so dis- 130
- posed on said shell that the perforations of several will be intersected by a single plane passed through said shell at right angles to the longitudinal axis thereof. 70
10. A suction roll shell for paper making machines provided with a plurality of endless lines of perforations each such line comprising several curves and said lines being so disposed on said shell that the perforations of several will be intersected by a single plane passed through said shell at right angles to the longitudinal axis thereof, the curves formed by such intersections being equally, oppositely inclined in diametrically opposite parts of the cross section of the shell so made. 75
